CHARLES DIEDRICH, SR., OF HACKENSACK, NEW JERSEY.

COMPASSES AND DIVIDERS.

1,178,706.

Specification of Letters Patent. Patented Apr. 11, 1916.

Application filed May 25, 1915. Serial No. 30,319.

To all whom it may concern:

Be it known that I, CHARLES DIEDRICH, Sr., a citizen of the United States, and a resident of Hackensack, county of Bergen, 5 and State of New Jersey, have invented a certain new and useful Improvement in Compasses and Dividers, of which the following is a full, clear, and exact specification.

This invention relates to a class of instruments adapted to be used by draftsmen and 10 artisans.

My invention has for its object primarily to provide an instrument, or compass and divider designed to be employed by draftsmen, carpenters, builders, and other artisans 15 for facilitating the drawing of plans, and laying-out work, etc., and which is of a form adapted to be readily converted from a compass to a divider as well as permitting a 20 pencil of any desired length to be used in conjunction therewith in a manner whereby the instrument with the pencil may be carried in a pocket of a person without subjecting the point of the pencil to be broken as is 25 incident to the ordinary types of instruments of this class.

The invention consists essentially of two leg members which are pivoted together so as to be hingedly swung toward and from 30 each other, and on these leg members is provided a retaining device for locking the members against movement when in adjusted positions. One of the leg members has its free end sharpened to a point, while the second leg member is tubular in form for adjustably holding a pencil therein, and at the free end of the tubular member is provided a catch which serves as means for releasably holding the pencil against accidental movement 35 in this tubular member.

Another object of the invention is to provide a cap member adapted to be applied over the pointed end of the pencil so as to be removably held on the free end of the 45 tubular leg member to prevent the pencil point from being broken, and this cap is tapered to a sharp point for serving as a complementary line-marker to the sharpened free end of the first leg member when the 50 instrument is used as a compass.

A further object of the invention is to provide a compass and divider of a simple and efficient construction, and which is susceptible of being made so as to combine 55 great strength and durability.

A practical embodiment of the invention

is represented in the accompanying drawing forming a part of this specification in which similar characters of reference indicate corresponding parts in all the views, the said 60 invention being more fully described herein-after, and then pointed out in the claims at the end of the description.

In the drawing, Figure 1 is an elevation, partly broken away, of one form of compass 65 and divider embodying my invention. Fig. 2 is a section taken vertically through the tubular leg member of the instrument, and Fig. 3 is an enlarged sectional view taken on the line III—III of Fig. 2.

The instrument, or compass and divider has two leg members 10 and 11 which may be of any suitable diameters and lengths, and the upper ends of these leg members are pivoted together, at 12, so as to be hingedly 75 swung toward and from each other. The leg member 10 is of somewhat the form of an obtuse angle to provide an upper portion 13 and a lower portion 14 disposed angularly with relation thereto, and this lower portion 80 is tapered to a sharp free end. The leg member 11 is likewise of the form of an obtuse angle to provide an upper part 15 and a lower part 16 disposed angularly thereto, and this lower part of the second leg 85 member is tubular in form. By forming these leg members in the shape of an obtuse angle when their free ends are directed together the upper portions thereof will be spaced apart in diverging arrangement, and 90 in opposed parts of the inner edge of the upper portions of the members are recesses 17 and 18 respectively.

The tubular portion 16 of the leg member 11 is of a length so that the leg member is 95 considerably shorter than the leg member 10, and this tubular portion is adapted to receive a pencil, as 19. The formation of this tubular portion at an angle relatively to the upper portion 15 serves to permit a pencil 100 of a full length as well as a pencil of a shorter length to be accommodated in the instrument, and in order to allow the pencil to be easily adjusted upwardly and downwardly in the tubular portion, especially 105 when of a short length, part of this tubular portion is cut-out, as at 20. Part of the tubular portion of the leg member 11 adjacent to its free end is enlarged, as at 21, and this enlarged part is exteriorly threaded, at 110 22, while the part of the tubular portion between this threaded enlarged part and the

free end of the tubular leg is also exteriorly threaded, as at 23.

When the pencil has been adjusted in the tubular leg 11 so that its pointed end extends a suitable distance outwardly of its free end, and to releasably hold the pencil against accidental movement, a catch, as 24, is provided. The catch 24 is composed of a clip, or finger 25 which is substantially L-shaped to provide a vertically disposed arm 26 having one end welded, or otherwise secured to the tubular leg while the other part of this arm is bent outwardly of the leg and then turned inwardly at an angle to provide a transverse arm 27 movably extending through a slot, or opening 28 in the opposed part of the tubular leg. The clip, or finger 25 is made of spring metal which is tensioned to normally force the spring finger outwardly of the opening 28, and on the exteriorly threaded enlarged part 21 of the tubular leg 11 is threaded a sleeve-nut 29 which when rotated toward the free end of the tubular leg will engage the vertical arm 26 of the spring finger 25 for forcing the transverse arm 27 inwardly of the opening 26 of the tubular leg so as to engage the pencil in the tubular leg. The pencil will then be tightly held in the tubular leg for using the instrument as a compass, and when it is desired to loosen the pencil in the tubular leg the sleeve-nut 29 is reversely rotated. The tension of the L-shaped spring finger 25 will then cause its engagement with the pencil to be released, and the pencil may be removed from, or adjusted in a suitable manner in the tubular leg.

The instrument as thus provided may be employed as a compass by draftsmen, carpenters, builders, and other artisans for drawing plans, and laying-out work, etc., and in order to lock the leg members 10 and 11 against accidental movement when the members are adjusted in spaced relation, I provide a retaining device, as 30. The retaining device 30 has two bars 31 and 32. One end of the bar 31 is seated in the recess 17 of the upper portion of the leg member 10, and this end of the bar is pivoted, at 33, to the leg member. One end of the bar 32 is likewise seated in the recess 18 of the leg member 11, and this end of the bar is pivoted, at 34, to the second leg member. The opposite ends of both of the bars 31 and 32 are disposed in overlapping arrangement between the leg members of the instrument and through these ends of the bars are threaded holes in which is passed a set-screw 35. When the leg members 10 and 11 are spread apart a suitable distance by tightening the set-screw 35 the arms 31 and 32 of the retaining device 30 will be locked together, and in turn the leg members will be held against movement. By loosening the set-screw 35 the arms 31 and 32 will be

unlocked, and the leg members may then be adjusted to and from each other.

To permit the instrument to be converted from a compass to a divider, a cap member, as 36, is provided. The cap member 36 has a hollow body 37 which is tapered to a sharp point for serving as a complementary line-marker to the sharpened free end of the leg member 10. Extending upwardly from the hollow body 37 is an annular flange 38 which is interiorly threaded, at 39, as well as being exteriorly threaded, at 40, and this annular flange is of a diameter to adapt it to be screwed on the threaded end 23 of the tubular leg 11 of the instrument. The interior of the hollow body 37 of the cap member 36 is of a size to accommodate the pointed end of the pencil, and to convert the compass to a divider the cap member is disposed over this end of the pencil and screwed on the threaded end 23 of the tubular leg, after which the sleeve-nut 29 of the catch 24 is adjusted partly over the exteriorly threaded part 40 of the annular flange of the cap member and partly over the threaded enlarged part 21 of the tubular leg, the annular flange of the cap member being of a thickness to permit the sleeve-nut to be thus adjusted. In this manner when the instrument is converted to a divider for use in the customary way the cap member 36 will be removably held on the tubular leg member of the instrument.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope thereof.

Having thus described my invention, I claim as new and desire to secure by Letters Patent:—

1. In a compass and divider, two leg members pivotally connected so as to be swung to and from each other, one of the leg members having its free end sharpened to a point and the second leg member being tubular for reception of a pencil, a catch on the tubular leg member, adapted to engage the pencil for releasably holding the pencil against accidental movement when adjusted in the tubular leg member, and a cap member removably fastened on the free end of the tubular leg member, and inclosing an end of the pencil when projecting therefrom.

2. In a compass and divider, two leg members pivotally connected so as to be swung to and from each other, one of the leg members having its free end sharpened to a point and the second leg member being

- tubular for reception of a pencil, and a cap member removably fastened on the free end of the tubular leg member, and inclosing an end of the pencil when projecting therefrom.
3. In a compass and divider, two leg members pivotally connected so as to be swung to and from each other, one of the leg members having its free end sharpened to a point and the second leg member being tubular for reception of a pencil, a cap member removably fastened on the free end of the tubular leg member, and inclosing the end of the pencil when projecting therefrom, and a retaining device on the leg member for releasably locking the leg members against accidental movement when in adjusted positions.
4. In a compass and divider, two leg members pivotally connected so as to be swung to and from each other, one of the leg members having its free end sharpened to a point and the second leg member being tubular for reception of a pencil, a catch on the tubular leg member, adapted to engage the pencil for releasably holding the pencil against accidental movement when adjusted in the tubular leg member, a cap member removably fastened on the free end of the tubular leg member, and inclosing the end of the pencil when projecting therefrom, and a retaining device on the leg members for releasably locking the leg members against accidental movement when in adjusted positions.
5. In a compass and divider, two leg members pivotally connected so as to be swung to and from each other, one of the leg members having its free end sharpened to a point and the second leg member being tubular for reception of a pencil, the free end part of the tubular leg member having an opening and being exteriorly threaded, a spring finger on the tubular member, movable inwardly and outwardly of the opening so as to engage the pencil for releasably holding the pencil against accidental movement when adjusted in the tubular leg member, and a sleeve-nut threaded on the exteriorly threaded end of the tubular leg member for yieldingly forcing the spring finger into engagement with the pencil.
6. In a compass and divider, two leg members pivotally connected so as to be swung to and from each other, one of the leg members having its free end sharpened to a point and the second leg member being tubular for reception of a pencil, the free
- end part of the tubular leg member having an opening, and being exteriorly threaded, a spring finger on the tubular member, movable inwardly and outwardly of the opening so as to engage the pencil for releasably holding the pencil against accidental movement when adjusted in the tubular leg member, a sleeve-nut threaded on the exteriorly threaded end of the tubular leg member for yieldingly forcing the spring finger into engagement with the pencil, and a tapered cap member removably fastened on the free end of the tubular leg member, and inclosing the end of the pencil when projecting therefrom.
7. In a compass and divider, two leg members pivotally connected so as to be swung to and from each other, one of the leg members having its free end sharpened to a point and the second leg member being tubular for reception of a pencil, the free end part of the tubular member having an opening, and being exteriorly threaded, a spring finger on the tubular member, movable inwardly and outwardly of the opening so as to engage the pencil for releasably holding the pencil against accidental movement when adjusted in the tubular leg member, a sleeve-nut threaded on the exteriorly threaded end of the tubular leg member for yieldingly forcing the spring finger into engagement with the pencil, a cap member tapered to a pointed end, removably fastened on the free end of the tubular leg member, and inclosing the end of the pencil when projecting therefrom, and a retaining device on the leg members for releasably locking the leg members against accidental movement when in adjusted positions.
8. In a compass and divider, two leg members pivotally connected so as to be swung to and from each other, one of the leg members having its free end sharpened to a point and the second leg member being tubular for reception of a pencil, a catch on the tubular leg member, adapted to engage the pencil for releasably holding the pencil against accidental movement when adjusted in the tubular leg member, and a pointed member complementary to the sharpened end of the first leg member, removably held on the free end of the tubular leg member.

This specification signed and witnessed this twenty fourth day of May A. D. 1915.
